TESTING DEVICE.

1,258,636.

Specification of Letters Patent.

Patented Mar. 5, 1918.

Application filed March 6, 1917. Serial No. 152,665.

To all whom it may concern:

Be it known that we, ALFRED J. NEWTON, a subject of the King of Great Britain, and STANLEY M. FURNALD, a citizen of the United States of America, both residing in Rochester, in the county of Monroe and State of New York, have invented certain new and useful Improvements in Testing Devices; and we do hereby declare the following to be a full, clear, and exact description of the same, reference being had to the accompanying drawings, forming a part of this specification, and to the reference-numerals marked thereon.

15. The object of this invention is to provide means for testing the correctness of one or more of the variable factors in photographic or process color work, when changes are made in the other factors.

20. In the three-color process, three color-selection negatives of the subject are made on panchromatic or color sensitive plates, one through a red light-filter, another a green light-filter, and a third through a blue filter. An additional negative on a panchromatic plate is made behind a yellow filter in the four-color process, which compensates the sensitiveness of the photographic plate, so that the different colored parts of the subject will affect the plate with the same relative intensity that they present to the eye.

25. Printing plates, such as half-tone blocks are made from these negatives. The plate derived from the red selection negative is printed in blue-green ink, technically known as minus-red. The plate from the green selection negative is printed in minus-green or magenta ink, while the blue section plate is printed in minus-blue or yellow ink.

30. In four-color work a visual luminosity plate is printed in gray or black. These different ink impressions are printed one upon the other so that the final colored picture or reproduction results from the cooperation of all the superposed printings. They cannot, however, coöperate to give a correctly colored picture unless every ink impression is of correct density. For example, if we are reproducing a neutral gray object by the three-color process and our filters, inks and plates are all correct, but the exposures of the original negatives are incorrect, we would then fail to get a gray

reproduction in the final print because some 55 of the ink impressions would be wrong. If the blue-green ink impression was not sufficient in amount to absorb a correct amount of red, the print would show a reddish tinge where it should be gray. While we 60 have taken gray as an illustration, other colors may be similarly degraded.

The correctness of the ink impressions depends primarily upon correct densities in the color-selection negatives. Only when a set 65 of negatives is secured, all having the correct density, will the rest of the process follow easily. But correct negatives result only when the exposures through the different filters bears a correct ratio to each other. 70 Consequently a determination of this ratio is a prime essential in all good work.

In the few cases where such controlling factors as light rays, plates, and filters are all standardized, a manufacturer of photographic materials can supply the trade with sufficient data concerning the exposure ratios. It is, however, neither practicable nor possible for him to give data covering all 75 conditions met with in practice. The operator's lamps may be quite different from the manufacturer's standard; different light filters may be substituted; or plates of different color sensitiveness may be used. After every departure from the standard 80 conditions, the operator must redetermine the correct exposure ratio. The present invention is a ratiometer which, while designed for general testing, is especially adapted to such ratio determinations, allowing them to be made simply, quickly and cheaply on a single plate. The results of the test indicate not only the existing errors but their direction and amount.

One form of ratiometer embodying this 95 invention is shown in the accompanying drawings in which:

Fig. 1 is a plan view of the instrument. Fig. 2 is a vertical transverse section thereof with the test chart removed.

Fig. 3 is a perspective view of the test chart.

Fig. 4 is a diagrammatic sectional plan view of the instrument in use showing conventionally a camera lens and light filters.

Fig. 5 is a diagrammatic sectional elevation thereof.

The device comprises in general a test

chart slidable over a background which does not reflect or emit actinic light; at least it should not reflect enough light to affect a photographic plate even with the longest exposure used in a test. For convenience we shall refer to such a background as "black." One particular form of such a background is shown in the drawing. It consists of a rectangular box 1 of opaque material having a longitudinal rectangular opening 2 in its top or outer face 3. The bottom inner face of the box opposite opening 2 is covered with a layer 5 of black velvet or similar dead-black material which absorbs substantially all of the incident light. The box acts as a shade to cut off undesirable lateral light rays from the velvet. While the velvet alone may suffice in some cases, the use of a shade is generally preferable. The other interior surfaces, as well as the exterior surfaces of the box, are preferably covered with material of negligible light reflecting power like black paper. In Fig. 2 I have indicated at 27 the surfaces where the black paper may be employed.

Upon the upper face of the box are located two guides 4, 4 parallel to the sides of opening 2 and forming channels 6, 6 in which slide the reduced ends 7, 7 of the test chart 8. This structure permits the chart to be moved to any desired position over the background. In the preferred embodiment the guides and background are long enough to allow the test chart to be moved successively into five different non-overlapping positions. These positions are above or opposite the five areas 9, 10, 11, 12 and 13 of a gray strip mounted on one of the guides 4 adjacent opening 2. Each area is slightly longer than the width of the test chart and bears appropriate symbols indicating the light filters used when photographing the chart in its successive positions. For illustration, such symbols may be: No Filter, K3 Yellow, A Red, B Green, C Blue, the letters K3, A, B, and C being the well-known designations of "Wratten" filters.

Upon the chart 8 is a neutral black and white picture 14, such as a good portrait positive on bromid paper, showing a full scale of gradation. Below this picture are three areas, 15, 16, 17, colored with the regular printing inks and bearing suitable identification symbols such as Blue, Red, Yellow, these symbols in the present example being a compact way of indicating blue-green or minus-red ink, magenta or minus-green ink, and yellow or minus-blue ink respectively. A strip 18 of measured and graded neutral gray density areas is included on the chart adjacent the colored ink. Each density area requires twice the exposure of the next lighter one, although other ratios could be used.

In use the box is fastened to a copy board with the opening 2 and the chart 8 facing toward the camera 19, as diagrammatically shown in Figs. 4 and 5. The chart 8 is moved to a position over the "no filter" area 9. One of the same kind of color sensitive plates that are to be used in the process is placed in the camera at 20 and the latter arranged so that an image of the whole front of the ratiometer can be formed on the plate. Of course, the chart is illuminated by the same light sources that are employed in the regular color process work.

An exposure is now made without using any filter. This exposure is assumed to be correct and, being the easiest of all the exposures to determine, will always be approximately accurate in the hands of an experienced worker. Since we are concerned with ratios of relative amounts of exposure, absolute accuracy of this first exposure within considerable limits is not essential.

The importance and function of the black background will now be apparent. The first or "no filter" exposure will impress at 21 a latent image of the chart 8 onto the sensitive plate at one side thereof, as indicated in Fig. 4. But no latent image of the background will be formed because no light passes therefrom into the camera. Thus an area of the sensitive plate adjacent to the latent image at 21 is left wholly unaffected and free to receive subsequent images. Of course, between exposures the lens is capped.

In Figs. 4 and 5 numerals 24, 25, and 26, indicate respectively a K3 filter, a red filter, and a green filter, a blue filter being omitted. Such blue filter may be used separately if necessary. Figs. 4 and 5 indicate the position of the filters when making an exposure through the K3 filter under conditions which will now be described.

The chart 8 is next moved to position 10 above the K3 yellow area 10. A K3 filter is put in position and an exposure made. The length of this exposure will be greater than that of the "no filter" exposure and will only be estimated by the operator. What may be termed the "K3" latent image of the chart is thus impressed at 23 on the sensitive plate directly beside the "no filter" image at 21. Due to the dead-black character of the background, no additional light reaches the first latent image at 21 during the second exposure, and in general it will be evident that the background prevents any fogging or injury to any image during the subsequent exposures of the test.

The K3 filter is now replaced by a red one and the chart moved to the A red position (see Fig. 1) whereupon an estimated exposure is given to form the A red latent image on the plate beside of and in line with the prior images at 21, 22. By similar procedure the B green and the C blue latent

images of the chart are impressed in proper position on the plate.

During all the above successive exposures the areas 9, 10, 11, 12, 13, are exposed repeatedly. Consequently, if they were ordinary white areas with black letters, they would be greatly overexposed when the test was finished. To prevent this trouble, they are made with black symbols on a deep gray ground, which needs a full exposure, such as is furnished by the sum of the successive test exposures, in order to appear satisfactorily in the final test print. We consider this arrangement preferable to making the areas white and moving a mask with chart 8 so that all the areas are covered except the one below the chart.

The sensitive plate now contains a set of latent images corresponding to the respective filters, and resulting from test exposures, the correctness of which the operator has tried to estimate. This plate is made into a negative from which a positive print may be made in the usual way. It is from the negative or this print that we tell whether the ratio of our trial exposures is in fact correct.

The print consists of five pictures of the chart 8 arranged side by side and each located above a symbol which identifies it; for example, the picture that has resulted from the exposure through the red filter will be above the words A Red.

If the operator has been fortunate enough to estimate the exposures correctly the first time, the area 14 and gradation strip 18 will appear of the same density in all the test pictures.

In the print of the picture taken through the red filter, area 15, which bears the word Blue, will be dark and areas 16, 17 very light. In the green filter picture, area 16 will be dark and the others lighter, while area 17 will be the darkest in the blue filter picture. The K3 picture shows the areas with visual luminosity. The areas 15, 16, and 17 thus test the coördination of the filters and inks.

If, as is probable, the estimated test ratio of exposures was somewhat incorrect, the pictures on the negative or in the test print will show the fact. For example, if the exposure through the green screen was too short, the resulting picture of 14 and the strip 18 in the final print will be too dark. If the exposure was too great, the resulting picture will be too light. This gives only a qualitative indication of the error, but inspection of such a picture is preferred by some workers. The pictures of the graded density strips 18 will, however, give a quantitative idea of the error when the densities in one picture are compared with those in another. For example, if the second density of the strip in a correct picture is equal to

the first density of the strip in an under-exposed picture, then the exposure in the latter case was only half what it should have been.

From the test print the operator has now learned the correct factors governing his work and is in a position to proceed in security to make the negatives for the color printing process. In cases where especial accuracy is necessary, the operator can, of course, make a second or even a third test to check up the original one, using in subsequent tests those exposures which were deduced from the prior ones.

The test itself, while somewhat complicated to describe, is in practice very short and simple. If desired, the test may be further shortened by omitting the making of a positive print, the necessary information being readily deducible from the test negative. It should also be noted that the order in which the exposures are made behind the different filters is immaterial, provided the chart 8 is located above the proper identification symbols during each exposure.

While we have explained how to find correct exposure ratios where the light source or the filters or the plates are varied, it is within the range of the instrument, should the exigencies of experiment require it, to keep the exposure ratio constant and vary other factors such as the filters until the pictures show equal densities.

While we have described the preferred embodiment of our invention, many modifications falling within the scope of the appended claims will readily occur to those skilled in the art.

We claim:

1. A photographic testing device including a black background and a member movable to selected positions thereover bearing a test area whereby the area may be photographed in successive positions under different conditions.

2. A photographic testing device including a black background, a member bearing a test area movable over the background to selected positions and identification symbols arranged along the background to indicate said positions.

3. In a photographic testing device a black background comprising an area of black material and means for shading the same from undesirable lateral light rays, and a test chart movable across said background.

4. In a photographic testing device a background composed of a box of opaque material having an opening in one face, and having its inner face opposite the opening covered with dead-black fabric and a test chart movable across said background.

5. A photographic testing device including a black background, guides thereon and

- 4
- a test chart movable over the background along said guides.
6. A photographic testing device including a black background, guides thereon, a test chart movable over the background along said guides to selected test positions and photographically reproducible identification symbols adjacent each position.
7. A photographic testing device including a black background, a testing chart movable thereon to selected positions and identification symbols on a deep gray ground adjacent said positions.
8. A photographic testing device including a black background and a test chart movable thereover, said chart bearing a neutral black and white picture, areas of colored ink with identification symbols thereon, and a strip of predetermined graded neutral gray densities.
9. A photographic testing device including a black background and a test chart movable thereover, said chart bearing a test strip of predetermined graded neutral gray densities.
10. A photographic testing device including a black background and a test chart movable thereover, said chart bearing areas of colored inks having identification symbols thereon.
11. A photographic testing device including a black background and a test chart movable thereover, said chart bearing a test strip of predetermined graded neutral gray densities.
- movable thereover, said chart bearing a graded, neutral, black and white image.
12. In a ratiometer for determining the exposure ratio in three and four-color process work, the combination of a black background, a test chart slidable thereover to selected test positions, each position corresponding to the use of a different light filter, and photographically reproducible symbols adjacent each position designating the light filter corresponding to the position.
13. In a ratiometer, a box of opaque material surfaced in black having a rectangular opening in its front face, the inner rear face opposite said opening being covered with black velvet, guides along the sides of said opening, a test chart slidable along said guides to successive positions, each position corresponding to a test exposure through a different light filter and black symbols on a gray ground mounted along one guide adjacent each position to designate the filter corresponding to the position.

In testimony whereof, we have signed this specification in the presence of two witnesses this 28 day of February, 1917, at Rochester, N. Y.
